[57] CLAIM

The ornamental design for a control panel for a vending machine or the like, as shown and described.

DESCRIPTION

FIG. 1 is a front and right side perspective view of a control panel for a vending machine or the like showing our new design;

FIG. 2 is a left side elevational view thereof;

FIG. 3 is a top plan view thereof;

FIG. 4 is a front elevational view of a second embodiment of the control panel illustrated in FIG. 1; and

FIG. 5 is a front elevational view of a third embodiment of the control panel illustrated in FIG. 1.

The bottom and rear of the control panel are flat and unornamented.

The broken line showings are environmental only and form no part of the claimed design.

FIG. 1

FIG. 2

FIG. 3

FIG. 4

FIG. 5
